[57] **CLAIM**

The ornamental design for a contour of an end portion of a closure flap of a portfolio or binder, as shown and described.

DESCRIPTION

FIG. 1 is an isometric view showing a portfolio or binder incorporating the present invention;

FIG. 2 is a top view of the portfolio or binder of FIG. 1; and, FIG. 3 is a side view of the portfolio or binder of FIG. 1. The file folder depicted by means of broken lines in the figures has been shown for illustrative purposes only and forms no part of the claimed design.
